SUCTION GATHERING CUP

Application filed March 15, 1928. Serial No. 261,748.

My invention relates to the art of handling molten glass in the processes of fabricating glassware.

More specifically the object of this invention is to provide improved means for making a vacuum connection with the inside of a suction mold or gathering cup employed in separating individual quantities of glass from a supply, each suitable for a single article.

One method of obtaining charges of molten glass is by means of a suction gathering cup which may in itself serve as a mold or as a transfer device for transferring a charge from a supply of glass to the mold proper. Heretofore two alternative undesirable results have attended the use of such devices. If the opening through which the air or gas was drawn out of the gathering chamber was relatively large, there existed a tendency for the molten glass to be drawn into or through such opening with consequent clogging of the opening because of the "freezing" of the glass therein. If, on the other hand, such openings were made sufficiently small to overcome this difficulty, the vacuum was not created in the gathering chamber as promptly as is desirable. It is toward the overcoming of these difficulties that this invention is primarily directed.

In order to more clearly explain the invention, one embodiment thereof is shown in the accompanying drawings, in which:

Figure 1 is a sectional plan taken on the line 1-1 of Fig. 2, and shows the suction head of a gathering cup; and

Fig. 2 is a sectional elevation showing the suction head with the associated gathering chamber and suction duct.

In the drawings, the numeral 11 indicates a gathering cup body having a gathering chamber 12 and an opening 13 which connects with a suction duct 14. This suction duct 14 may be formed in a cup supporting and operating arm 15 having a holder 16 in which the cup 11 fits closely and is held removably in place by a set screw 17 and lock nut 18. As shown, a removable and replaceable sectional head fits in the opening 13. This head preferably comprises an inner or central section 19 having

the form of a solid cylinder and other sections 20, 20 having the form of cylindrical sleeves, all arranged concentrically with respect to one another and to the wall of the opening 13. Each of the sections has a close fit at its upper end or the end nearest the suction duct with the adjacent section, and the outer section of the head has a close fit adjacent to its upper end with the wall of the opening 13, whereby the removable head is held in place 60 against lateral movement. A pin 21 extends through aligned transverse openings in all the sections of the head and has its ends projecting into aligned openings in the surrounding portion of the cup body, whereby 65 the head will be held against axial displacement in the head opening 13, but can be conveniently removed and replaced when the pin 21 has been removed. The holder 16 prevents displacement of the pin 21 when the cup 70 is held in place in the holder.

A plurality of very narrow annular openings or orifices 22 are provided in the head in communication with the gathering chamber. These openings 22 may be provided by forming the portions of the sections of the head adjacent to the chamber 12 of less diameters than the diameters of the adjacent surrounding walls, as shown, although it is obvious that each of such openings may be formed in part in a section of the head and in part in the wall surrounding that section, or wholly in the wall surrounding each section of the head. In the construction illustrated in the drawings, the annular openings 22 extend 75 only part way longitudinally of the head and the outer diameters of the head sections adjacent to the duct 14 are greater than the outer diameters of the portions of such sections adjacent to the chamber 12. While these openings 22 are very small in one dimension, the radial dimension thereof being only a few thousandths of an inch, the total length or circular dimension of each opening is such as to provide a total orifice area sufficient to 80 permit a quick application of vacuum. By providing a plurality of such annular orifices, the total area of the suction opening or port is still further increased.

These narrow orifices being primarily pro- 100

vided for the purpose of permitting a quick application of vacuum without permitting the entrance of molten glass thereinto, it is possible to provide larger passages above these narrow annular orifices. As shown, each of the narrow annular openings 22 is enlarged at its upper end to provide an annular groove 23 of substantially greater width. The grooves 23 are located in the head between the end adjacent the chamber 12 and the end adjacent the duct 14 and are connected by longitudinal grooves 24 with the suction duct 14.

It will be seen that means have been thus provided for preventing the passage of the molten glass into the suction orifice or the clogging of the suction passages because of glass drawn thereinto and at the same time the total area of such orifices is sufficient to permit a quick application of vacuum.

The application of suction through the suction orifices or passages will cause the cup chamber to be filled uniformly with glass throughout the cross section of the cup 25 chamber. If desired, pressure may be admitted through the same orifices or passages at the proper time to eject the glass from the cup.

The cup may be made of metal or of suitable 30 composition, such as brush carbon, which will minimize the surface chill imparted to the glass and to which the molten glass will not stick, or with metallic outer walls and an inner lining of a suitable composition, such 35 as is disclosed in my copending prior application, Serial No. 203,391, filed July 5, 1927, for mold charge collecting device.

While the description of the invention given above refers particularly to a suction 40 gathering cup of the type which draws its charge upward from the surface of a pool of molten glass, the invention is also applicable to a collecting receptacle of the type which receives its charge from an outlet located 45 above the receptacle. It may be desirable to create a vacuum in such a collecting receptacle at the time that the glass enters thereinto, to prevent air from remaining in the cup and causing bubbles in the glass, to effect quick 50 and uniform filling of the cup, and to minimize unequal chilling of the glass entering the cup. It will be understood that this use, as well as the one hereinbefore described is contemplated as being within the scope of 55 my invention.

It will also be understood that the embodiment of the invention shown above is for the purpose of illustration only, and various modifications may be made therein without 60 departing from the spirit and the scope of the invention, as defined in the subjoined claims.

I claim:

1. A suction gathering cup having a removable suction head at one end thereof, said head being formed of sections, said sections

having transverse openings therein aligned with each other, said cup having an opening aligned with said transverse openings, and a pin received in said aligned openings.

2. A suction gathering cup having a removable suction head at one end thereof, said head being formed of sections having transverse openings therein aligned with each other, said cup having an opening aligned with said transverse openings, a pin received in said aligned openings, a holder fitting over said cup and the ends of said pin, and means for retaining said holder in place.

3. A suction cup for glass working machinery having a chamber and a cylindrical suction head removably secured in an opening in one end of the cup, the end of said cylindrical head adjacent to said chamber being of slightly less diameter than said opening.

4. A suction cup having a chamber and a cylindrical suction head in an opening in one end of the cup, said head having an annular groove intermediate its ends, and a longitudinal groove between said annular groove and one end of said head, the diameter of said head being slightly less than said opening between said annular groove and the other end of said head.

5. For a suction gathering cup having a gathering chamber and a cylindrical opening, a sectional head comprising a plurality of concentric cylindrical sleeves, each sleeve being of slightly less diameter at its end adjacent to said chamber than the opening in which it is placed, said head also having passages for placing the spaces between the sleeves in communication with a source of suction.

6. For a suction gathering cup having a gathering chamber and a cylindrical opening, a sectional head comprising a plurality of concentric cylindrical sleeves, each sleeve having an annular groove intermediate its ends, a longitudinal groove between said annular groove and one end of said sleeve, each sleeve being of slightly less diameter between said annular groove and the other end of said sleeve than the opening in which it is placed.

7. In combination, a suction gathering cup having a gathering chamber, a supporting arm having a suction duct, a cylindrical opening between said chamber and said duct, and a plurality of concentric members in said opening, each member having an annular groove intermediate its ends, a longitudinal groove between said annular groove and said suction duct and thin annular passages between said annular groove and said chamber, and means for holding said members in said opening.

Signed at Hartford, Connecticut, this 10th day of March, 1928.

KARL E. PEILER.
